US0D1052188S

(12) **United States Design Patent** (10) **Patent No.:** **US D1,052,188 S**
(45) **Date of Patent:** **** Nov. 19, 2024**

(54) **MANDIBLE GUARD**

(71) Applicant: **Galvion Ltd.**, Portsmouth, NH (US)

(72) Inventors: **Edward R. Hall**, Starksboro, VT (US); **Stéphane Lebel**, St. Redempteur (CA); **Dominic Giroux Bernier**, St-Gabriel de Brandon (CA); **Bastien Jourde**, Montréal (CA); **Philippe Lefebvre**, Montréal (CA); **Hugues Rivest**, Montréal (CA)

(73) Assignee: **Galvion Ltd.**, Portsmouth, NH (US)

(**) Term: **15 Years**

(21) Appl. No.: **29/782,670**

(22) Filed: **May 7, 2021**

(57) **CLAIM**

The ornamental design for a mandible guard, as shown and described.

DESCRIPTION

FIG. 1 is a top, front, right side perspective view of a mandible guard showing our new design; FIG. 2 is a front elevation view thereof; FIG. 3 is a rear elevation view thereof; FIG. 4 is a left side elevation view thereof; FIG. 5 is a right side elevation view thereof; FIG. 6 is a top plan view thereof; and, FIG. 7 is a bottom plan view thereof.

The broken lines shown in the drawings represent portions of the mandible guard that form no part of the claimed design.

1 Claim, 6 Drawing Sheets
